FLANGE VALVE

Ladd M. Adams, Norman, Okla., assignor to Balon Corporation, Oklahoma City, Okla., a corporation of Oklahoma

Filed Aug. 26, 1966, Ser. No. 3,600

Term of patent 14 years

(Cl. D91—3)

FIG. 1 is a perspective view of a flange valve showing my novel design.

FIG. 2 is an end view thereof.

FIG. 3 is a side view thereof.

FIG. 4 is a bottom plane view thereof.

FIG. 5 is a top plan view thereof.

The broken line representation of flanges and bolts in FIGS. 2 and 3 are for purposes of illustration only.

I claim:

The ornamental design for a flange valve, as shown and described.
